UNITED STATES PATENT OFFICE.

WILLIAM P. PHILLIPS, OF BOSTON, MASSACHUSETTS.

LUBRICATOR.

SPECIFICATION forming part of Letters Patent No. 367,059, dated July 26, 1887.

Application filed March 25, 1887. Serial No. 232,373. (No model.)

To all whom it may concern:

Be it known that I, WILLIAM P. PHILLIPS, of Boston, county of Suffolk, and State of Massachusetts, have invented an Improvement in Lubricators, of which the following description, in connection with the accompanying drawings, is a specification, like letters on the drawings representing like parts.

This invention has for its object to provide a lubricator with a retaining device for the valve which controls the discharge of oil, whereby the valve may be gradually opened and afterward held open until positively closed.

In accordance with the invention the valve is normally held against its seat by spring-pressure, and the upper end or head of the valve-stem is provided with a laterally-projecting pin or stud which remains just above the upper side of an adjustable cap or nut when the valve is seated, said adjustable cap turning upon the upper screw-threaded end of a tube inclosing the spring-held valve-stem. A projection rises from the upper side of the adjustable cap, it having a flat bearing-surface at the top provided with a central groove or recess which receives the pin or stud projecting from the valve-stem, and also having inclined sides leading from the top of the projection to the top of the cap, over which the pin or stud rides as the valve is rotated to thereby gradually raise the valve from its seat a distance equal to the height of the projection. The pin or stud is fixed to the valve-stem, and is of sufficient length to serve as a means for rotating it. A suitable clamping device is provided for securely binding or setting the cap or nut at any desired point it may be placed.

Figure 1 shows in vertical section a lubricator provided with a retaining device for the valve embodying this invention; Fig. 2, a side elevation of the adjustable cap or nut, the retaining device, and a portion of the valve-stem; and Fig. 3, a top view of the adjustable cap or nut provided with the clamping device.

The oil-reservoir a , its discharge passage or nipple a' , and the discharge-tube a'' , constructed to support the lubricator, the valve-stem a^3 , having the conical end to enter the discharge-nipple and seat itself as a valve, the inclosing-tube a^4 for the valve-stem, having the holes 12 and the spring a^5 , are all as usual. The

upper end of the tube a^4 is screw-threaded to receive the cap or nut c , which is provided upon its upper side with a projection, c' , having a flat top, 2, a central recess or groove, 3, and the inclined sides 4, the projection c' being made of the height that it is desired the valve shall rise from its seat.

A pin or stud, d , is fixed to the head a^6 of the valve-stem and projects laterally therefrom. The pin or stud normally remains just above the upper side of the cap c when the valve is seated by the pressure of the spring a^5 , said pin or stud being so rigidly secured to the head of the valve-stem as to serve as a handle, by means of which the said stem may be rotated.

As the valve stem is rotated by the pin or stud, or in any manner, the said pin or stud passes up the inclined side 4 of the projection c' and rests for a moment upon the flat top part, 2, and then enters the central groove or recess, 3, in which recess it remains as long as it is desired to retain the valve open.

By providing an inclined passage, 4, for the pin or stud, as described, the valve may be opened gradually, and by providing a flat portion, 2, somewhat higher than the bottom of the recess 3, the valve may be opened a little more at the start to establish the flow of oil, after which the pin entering the recess retains the valve the desired distance from its seat.

I am aware that means have been provided for raising the valve from its seat and afterward keeping it open a definite distance; but such construction I do not, broadly, herein claim.

The cap or nut c is slotted from its outer edge inward beyond the center, as at 6, and a portion of the cap is removed to receive the head of a binding-screw, c^2 , which passes through the cap tangential to the axis of rotation of the valve-stem, said binding-screw joining the two portions of the cap divided by the slit 6 and acting to bind the cap firmly to the screw-threaded portion of the tube a^4 at any desired height at which it may be set. By applying the binding-screw in this manner it is very effectual in the accomplishment of the result desired, and is removed from the remaining parts.

I claim—

1. In a lubricator, the oil-reservoir, dis-

charge-nipple, valve, valve-stem, and inclosing-tube a^4 , combined with a pin or stud, d , projecting laterally from the valve-stem, the cap or nut c , and a projection rising from the cap c , it having an inclined side, 4 , and a pin-receiving groove or recess, at the top of the projection, substantially as described.

2. In a lubricator, the oil-reservoir, discharge nipple, valve, valve-stem, and inclosing-tube a^4 , combined with a pin or stud, d , projecting laterally from the valve-stem, and a cap, c , having a projection, c' , the inclined side 4 , flat top portion, 2 , and a pin-receiving groove or recess, 3 , substantially as described.
- 15 3. In a lubricator, the oil-reservoir and dis-

charge-nipple and valve controlling the discharge-nipple, combined with an adjustable nut, c , slotted, as at 6, and cut away, and a binding-screw, c^2 , joining the two portions of the cap divided by the slit, the head of the screw c^2 entering the cut-away portion of the cap, substantially as described.

In testimony whereof I have signed my name to this specification in the presence of two subscribing witnesses.

WM. P. PHILLIPS.
